UNITED STATES PATENT OFFICE.

GUSTAV SCHOCK, OF NEW YORK, N. Y.

BARREL-WASHER.

SPECIFICATION forming part of Letters Patent No. 570,610, dated November 3, 1896.

Application filed January 16, 1896. Serial No. 575,688. (No model.)

To all whom it may concern:

Be it known that I, GUSTAV SCHOCK, a resident of the city, county, and State of New York, have invented certain new and useful 5 Improvements in Keg-Scrubbing Machines, of which the following is a specification.

My invention relates to keg-scrubbing machines; and it has for its object to produce a simple, cheap, and effective machine which 10 will thoroughly scrub kegs, barrels, and the like.

To this end my invention consists in the construction hereinafter set forth and claimed.

My invention will be understood by reference to the accompanying drawings, in which—

Figure 1 is a side elevation of a keg-scrubbing machine embodying my invention. Fig. 2 is a plan view thereof, and Fig. 3 is a section taken on line 3 3 of Fig. 2 to more clearly show the construction and mode of operation.

In the drawings, in which like letters of reference indicate like parts, A is the framework of the machine, on which is journaled a pair 25 of shafts B and C. Brackets D E are provided, which are adjustable up and down in the frame. These brackets support pivoted brush-carriers G H, which are horizontally adjustable in the brackets and support 30 brushes I J, which brushes serve to cleanse or scrub the ends of the keg, as will be pointed out.

Mounted in the framework A is a vertically-sliding cross-bar K to which is pivoted a brush L, the pivot l serving to form the connection between the brush and cross-bar. The cross-bar slides in ways a a in the frame and is connected to pivoted link-adjusting mechanism comprising the rock-shafts b c 40 and the system of links d e f g, and the handle h, and likewise the system of links i j combined with the rock-shafts b and c and the handle k. A sleeve M is rigidly connected with and carried upon the shaft B, and has secured or mounted thereto eccentric wheels 45 N O, the highest portion of the eccentric wheel N being opposite to the lowest portion of the eccentric wheel O, as indicated in dotted lines in Fig. 3. The shaft C is similarly 50 provided with a sleeve M', upon which eccen-

tric wheels N' O' are carried in a like manner to the wheels N O.

It will be observed that by mounting the eccentric disks upon the sleeves M M' in the manner indicated the relationship of the disks 55 connected with each sleeve cannot be altered even if the position of a sleeve upon one of the shafts is altered, and that a strong connection between the disks is provided. The shaft B derives its motion from a pulley P and carries a sprocket-wheel Q, which is geared with a similar sprocket-wheel R, carried by the shaft C, by a sprocket-chain or positive connection S.

The operation of my device is as follows: 65 A keg or barrel, as shown at X in dotted lines, is rested upon the wheels or rollers N O N' O', and the brushes are adjusted up to the keg. The shaft B is thereupon rotated, which rotates the wheels N O N' O'. The kegs 70 being carried on these wheels and the shafts being positively geared together, it follows that the keg will be given a motion of translation by being raised, first one end of the keg and then the other, by reason of the eccentric 75 mounting of the wheels, and that in addition to this motion of translation or oscillation of the keg the same is caused to revolve. Thus a very efficient and thorough scrubbing of the keg will take place. 80

It will be seen that by my invention I provide a simple, cheap, and efficient keg-scrubbing machine wherein the pivoted end brushes I J automatically adjust themselves to the keg irrespective of the position of the keg upon 85 the rolls, and that the pressure of the brush L against the keg may be increased or decreased at will. It will also be observed that the arrangement of the parts in the machine allows of the keg being readily placed in position and removed from the machine. 90

What I claim, and desire to secure by Letters Patent, is—

In a keg-scrubbing machine, the combination of a framing pivoted end brushes freely 95 movable around the pivots thereof and horizontally and vertically adjustable in said framing, shafts B, C, eccentrically-mounted rollers N, O, N', O', carried upon said shafts, the highest portions of the eccentric wheels 100

upon the shafts at one end being opposite to the lowest portion of the eccentric wheels at the opposite end, a pivoted vertically-adjustable brush freely movable around its pivot, 5 said brush being mounted in said framing between the eccentric wheels and on a lower plane than the side brushes, and toggle mechanism for adjusting said brush vertically and

for holding the brush in its adjusted position, whereby the amount of pressure exerted by 10 the brush upon the keg may be increased or decreased at will, substantially as described.

GUSTAV SCHOCK.
